UNITED STATES PATENT OFFICE.

SAMUEL ARTHUR WILLIAMS, OF LOCKPORT, NEW YORK, ASSIGNOR TO THE ASBESTOS WOOD CO., OF NASHUA, NEW HAMPSHIRE, A CORPORATION OF MAINE.

SMOKE-JACK.

1,244,156.

Specification of Letters Patent.

Patented Oct. 23, 1917.

Application filed July 21, 1917. Serial No. 182,073.

To all whom it may concern:

Be it known that I, SAMUEL ARTHUR WILLIAMS, a citizen of the United States of America, and resident of Lockport, in the county of Niagara and State of New York, have invented new and useful Improvements in Smoke-Jacks, of which the following is a specification.

This invention relates to the construction 10 of smoke jacks and like ventilating funnels, the invention involving a modified and improved form of the apparatus disclosed in Patent No. 955,290, granted to W. K. Seigel April 19, 1910.

15 In locomotive roundhouses and the like, where the smoke from locomotive funnels is emitted through the roof, the smoke jacks employed to conduct the smoke and gases through the roof are subjected to high temperatures, to the corroding action of the exhaust gases, to excessive vibration due to the pulsations of the locomotive exhaust, and to other severe conditions. Heretofore smoke jacks have usually been made of 20 sheet iron or steel, reinforced at their joints by angle irons, and while these smoke jacks have been fairly well adapted to resist the high temperatures, they have not served to insulate the surrounding portions of the 25 roundhouse from the heat of the engine, and they have been exceedingly shortlived owing to the fact that the acidulous gases from the locomotives rapidly disintegrate the metal. Moreover, the pulsations of pressure produced by the locomotive exhaust 30 tend to loosen and break the fastenings, especially after the jack has been subjected to the action of the gases for a considerable period of time. It has also been proposed 35 to construct smoke jacks of flat plates of refractory material secured to angle-iron framework, but the destruction of the framework and fastenings in this type of smoke jack has proceeded in the same way 40 and from the same causes as above mentioned, thereby rendering the smoke jacks unfit for further use or even for successful repair after a comparatively short time. Thus, square or angular corners, which have 45 been characteristic of most types of smoke jacks, have proved to be detrimental whether the walls of the jack be formed of metal or of refractory material.

50 As in the prior patent above referred to,

I propose to employ such materials and to 55 shape the jack so as to remedy the defects inherent in the above mentioned types of apparatus, to reduce the number of metal fastenings to a minimum, and to render it possible effectively to protect the exposed 60 portions of metallic fastenings against corrosion. The material which I preferably employ possesses ample physical strength, 65 is non-combustible and is non-corrodible in the presence of acidulous gases. This material is formed as disclosed in the prior Patent 969,202, granted to E. Sobel, W. Gold, and J. Stretch September 6, 1910, which in brief is as follows:—

A mixture is first made comprising substantially equal quantities by weight of either very short asbestos fibers or the asbestos fibers produced by grinding serpentine rock, and a cementitious material which may be either Portland cement or finely comminuted magnesium oxid. With these solid ingredients is then made a pulp or dough, using a weight of water about equal to the whole weight of the solids. Immediately after the formation of the 70 wet pulp it is subjected to a pressure of about 1000 pounds to the square inch in a hydraulic filter press, after which the felted sheet thus made is withdrawn and drenched with water. The sheet absorbs 75 this supplemental supply of water to such an extent as to be rendered plastic, and it retains this plasticity for a sufficient time 80 to allow the sheet to be molded into almost any desired curved form over suitably shaped wooden molds. As the cementitious material in these plastic bodies begins to set from the time the wet pulp is made, it is necessary to give the sheets their final desired shape before the setting operation 85 has proceeded too far. In practice it has 90 been found to be necessary to complete the manufacture of the molded sheets within fifteen or twenty minutes after the sheets have been taken from the press. When 95 100 sheets of this character are completed they can be readily drilled and shaped with ordinary tools, and by reason of their heat and acid resisting qualities are well adapted to the construction of my improved jack.

105 The principal objects of the present invention are to produce smoke jacks and the like which are exceedingly substantial and

durable, and which are adapted to withstand high temperatures, vibration and the action of acidulous gases.

Other objects of the invention will be 5 apparent from the following description and the accompanying drawings, in which—

Figure 1 is a side elevation of one embodiment of my invention;

Fig. 2 is an end elevation of the embodiment shown in Fig. 1;

Fig. 3 is a horizontal cross-section of the stack portion of the jack;

Fig. 4 is a plan view of the means for connecting the stack to the base, showing 15 the stack in cross-section; and

Fig. 5 is a section through the preferred means for securing the parts together.

The particular embodiment of my invention illustrated in the drawings comprises 20 in general a base portion 1, a stack portion 2, and means 3 for connecting the stack to the base. It will be understood that the stack is intended to pass through the roof of a roundhouse or the like, and I have 25 therefore illustrated a portion of a roof 4 and means for forming a tight joint between the stack and the roof comprising a flashing 6 and a spacing member 7 adapted to fit between the sloping roof and the horizontally disposed flashing 6, these parts being 30 secured together in any suitable manner. It is also desirable to employ a cap member over the stack, and I have therefore illustrated such a cap member at 8, this member 35 being mounted on the stack by means of a pair of straps 9 extending upwardly from each side of the stack.

The base portion 1 of my improved smoke jack preferably comprises four members 11 40 so shaped and positioned as to form a truncated pyramid having rounded corners, the members being secured together at the sides of the base by means of bands 12 and at their ends by bands 13. The V-shaped opening 14 formed at each side of the base 1 is 45 preferably covered over by means of a gusset plate 16. The rounded corner members 11 and the gusset plate 16 are preferably formed of the asbestos-form material 50 above described, and while the straps 12 and 13 may also be formed of this material, they are preferably formed of metal, inasmuch as they are disposed wholly on the outside of the base and therefore do not come in 55 contact with the exhaust gases.

The stack 2 is preferably formed of four strips of material, namely, a pair of side strips 17 and a pair of end strips 18. These strips are overlapped at the four corners 60 of the stack, the stack preferably having the shape of a flattened drum, and the overlapping portions of the strips are secured together by means of bolts or rivets 19. It is essential that the overlapping portions of 65 the sheets be disposed at the corners of the

stack, and not at the sides and ends, particularly not at the sides. As above stated, the pulsations in pressure produced in a smoke jack tend to force the walls of the stack outwardly so that the side walls are 70 vibrated inwardly and outwardly to a certain extent. I have found that by disposing the overlapping portions of the side and end walls at the corners of the stack, the stack is not only thereby made more rigid, but 75 the vibrations produced by the pulsations of pressure do not loosen the fastenings between the respective sheets, especially where the overlapping portions are rounded so as to be made more rigid. On the contrary, 80 what little vibration that may take place with my improved construction, takes place throughout the broad side walls 17, the flexing of the side walls occurring not at the points of connection with the end walls, but 85 at and between points 21 where the side walls begin to curve. If the connection between the sheets of material making up the stack were disposed in the central transverse plane of the stack they would be disposed in the region of maximum vibration, but when disposed at the corners as in my 90 improved construction the connections are disposed at the regions of least vibration and are therefore not loosened by the vibration. 95 And owing to the unique method of connecting the side and end walls together, namely, by overlapping them so as to form rounded corners, the square corners heretofore employed are avoided, together with all the 100 disadvantages incident thereto. The sheets 17 and 18 are preferably formed of asbestos-form fiber as above described, these sheets being formed into the shape shown in Figs. 3 and 4 when manufactured.

The means for connecting the stack 2 to the base 1 comprises a collar 3 which, while it may be made of two parts as shown in Figs. 1 and 2, is preferably made up of angle irons equal in number to the number of sheets in the stack, namely, four, as shown at 22, 23, 24 and 25 in Fig. 4. These angle irons fit into the angle between the stack and the base and are secured to the stack and base by means of rivets or bolts 26. The angle irons are provided at their ends with radial flanges 27 which are secured together by means of bolts 28 so as to form a complete ring about the jack. The angle irons which are secured to the overlapping pair 110 of stack sheets, namely, the end sheets 18 in the drawings, have shorter end flanges 27 than do the angle irons which are connected to the other pair of stack sheets, namely, pair 17. Thus, the vertical portions of the angle irons of both the end and side irons 115 may lie against the corresponding sheets of the stack, the respective angle irons being equal in length to the exteriorly exposed portions of the stack sheets. The angle irons 120

are preferably formed of cast iron, and they may, if desired, be provided with radial ribs 29 intermediate their ends, as shown on angle irons 23 and 24, in order to strengthen 5 the connection between the base and stack.

Suitable means for connecting the various parts together is shown in Fig. 5. This fastening means comprises a bolt 31 passing through the overlapping sheets of material 10 32 and being provided with washers 33. In order to protect the bolt and washers from the action of the acidulous gases in the locomotive exhaust the ends of the bolts and the washers are covered over with a material 15 34 which is adapted to withstand the chemical action of the gases, a suitable material for the purpose comprising protective cement.

I claim:

1. A smoke jack comprising a plurality 20 of strips of material joined together so as to form an inclosed passage therethrough, the smoke jack having a rounded corner, and the strips being overlapped throughout the rounded corner.

2. In a smoke jack, a stack having the shape of a flattened drum, the sides and ends of the stack comprising separate strips of material overlapping throughout the rounded corners of the stack, and means 30 for securing the overlapping portions of said strips together.

3. In a smoke jack, a drum-shaped stack comprising side walls and end walls composed of molded felted homogeneous cement- 35 united asbestos fiber, the side walls and end walls overlapping at the corners of the stack in smoothly rounded curves, and means for securing the side and end walls together throughout the overlapping portions.

4. In a smoke jack, the combination of a truncated pyramidal base comprising curved corner pieces and gusset plates, a conoidal thimble surmounting the truncated apex of 45 the base, and a stack surmounting the thimble, those members having curved surfaces being composed of molded felted homo-

geneous cement-united asbestos fiber, and the side and end walls of the stack being overlapped throughout the major portion of the rounded corners of the stack. 50

5. In a smoke jack, the combination of a truncated pyramidal base, a stack surmounting the truncated apex of the base, the stack comprising side and end walls 55 overlapped to form rounded corners of double thickness, and means for connecting the stack to the base, the connecting means comprising parts secured respectively to the side and end walls of the stack. 60

6. In a smoke jack, the combination of a truncated pyramidal base, a stack surmounting the truncated apex of the base, the stack comprising a pair of side walls and a pair of end walls, one pair of walls 65 overlapping the other pair of walls so as to form rounded corners of double thickness, and means for connecting the stack to the base, the connecting means comprising a collar fitting into the angle between the 70 stack and the base and being secured to said side and end walls.

7. In a smoke jack, the combination of a truncated pyramidal base, a stack surmounting the truncated apex of the base, 75 the stack comprising a pair of side walls and a pair of end walls, one pair of walls overlapping the other pair of walls so as to form rounded corners of double thickness, and means for connecting the stack to the 80 base, the connecting means comprising four angle irons fitting into the angle between the stack and the base and having radial flanges at their ends for securing them together in the form of a closed ring, the 85 flanges on the angle irons connecting with the overlapping pair of walls being shorter than the flanges on the other angle irons so that each angle iron fits against a wall of the stack. 90

Signed by me at Lockport, New York, this 14th day of July, 1917.

SAMUEL ARTHUR WILLIAMS.
